United States Patent Office

Des. 222,793
Patented Jan. 4, 1972

222,793

BROOM HEAD

Donald G. Ray, Winnsboro, Tex., assignor to All-American Manufacturing, Inc., Garland, Tex.

Filed Apr. 30, 1970, Ser. No. 22,743

Term of patent 14 years

Int. Cl. D4—01

U.S. Cl. D4—4

FIG. 1

FIG. 2

FIG. 3

FIG. 4

FIG. 5

FIG. 1 is a top perspective view of a broom head showing my new design;

FIG. 2 is a front elevation view thereof;

FIG. 3 is a side elevation view thereof;

FIG. 4 is a bottom view thereof; and

FIG. 5 is a top view thereof.

I claim:

The ornamental design for a broom head, substantially as shown.
